Attorney.*

UNITED STATES PATENT OFFICE.

JOHN MUTTON, OF CLEVELAND, OHIO.

SAFETY APPARATUS FOR ELEVATORS.

1,304,798.

Specification of Letters Patent.

Patented May 27, 1919.

Application filed November 22, 1915. Serial No. 62,710.

To all whom it may concern:

Be it known that I, JOHN MUTTON, a citizen of the United States of America, residing at Cleveland, in the county of Cuyahoga and State of Ohio, have invented certain new and useful Improvements in Safety Apparatus for Elevators, of which the following is a specification.

My invention relates to improvements in safety apparatus for elevators, and more particularly to such apparatus as is adapted for electrical actuation; the objects of my improvement being to prevent the movement of the elevator car at all times except when the doors or gates are closed; to prevent the opening of the doors or gates at all times except when the car is standing at the corresponding level of any one of the gates; to automatically disconnect the actuating current when the car is out of service; to afford proper signals for indicating the operating conditions and generally for the improvement of the elevator control, as will appear in and by the following specification.

My improvements are herein shown somewhat diagrammatically, in connection with an elevator equipped with vertically sliding gates, and provided with an electro-mechanical control therefor, and with electric signal lights, although said invention is not necessarily limited to the details which I shall hereinafter explain.

Referring to the accompanying drawings, in connection with which I may best explain my invention:

Figure 1 illustrates partially in diagram and partially in vertical section, an elevator shaft, an elevator car, electrical circuits and associated safety apparatus, for the control of said car and of the vertical sliding gates.

Fig. 2 is a view in side elevation, showing the mechanical gate-locking appliance and its circuit controlling apparatus.

Figs. 3 and 4, respectively show in front elevation partially broken away, and side elevation partially sectioned, the electrically actuated cable-gripping mechanism.

Fig. 5 is a transverse sectional view of a portion of the latter on line 5-5, Fig. 3; and Figs. 6 and 7 respectively, show in side and end elevations, the switching apparatus operated by the cable sheave.

Fig. 8 shows a compact type of controlling switch.

The same character of reference is em-

ployed throughout the different figures of the drawings to indicate similar parts.

The elevator car *a*, is supported by cables *a'*, in the usual manner, while a cam device *a''* at the side of said car, serves to operate the gate locking device, provided at each floor. The usual operating cable *c*, *c'* extends over top and bottom sheaves *b*, *b'*; the former being provided with a notched cam *b''*, which is adapted to operate the controlling switch for the electrical apparatus.

In addition to the automatic controlling switch just mentioned, said electrical apparatus comprises an additional two-position switch associated with the gate-locking apparatus at each floor level, and shown in Fig. 2, for the purpose of operating the floor signals and the cable-gripping mechanism. Said cable-gripping mechanism in turn, comprises an electrical solenoid operating in opposition to a spring, which normally tends to grip the operating cable and prevent the movement of the car. Thus the car and gates are made interdependent, while the energizing circuit is automatically disconnected to prevent the waste of current and possible damage to the solenoid, from overheating.

Current is supplied from the electrical mains + —, controlled by the hand switch *d*, from which conductors 1, 2, respectively lead to the gate locking appliances, and to the sheave-controlled switch, just above noted. The conductor 3 continues the circuit from said switch through the solenoid *e*, of the cable-gripping apparatus, from which conductor 4 further continues the circuit through a signal lamp *a'*, positioned within the car and to the opposite sides of the gate-lock circuits. Floor signals are also provided adjacent to each gate and locking device, as lamps *f*, *f'*, connected with conductor 2 while conductors 5 and 6 connect the same to the opposite side of the circuit. Conductors 7, in turn respectively connect the gate-lock switches with the main 1 of the controlling circuit.

A somewhat detail description of the associated apparatus must be here included, in order that the electrical features of my invention may be more readily grasped, although I do not necessarily confine my invention to the embodiment which is here chosen for extended explanation. Each of the gates *g*, *g'* is provided with a rack, as

g'', best shown in Fig. 2. This rack is mounted upon the gate in position normally to engage the switch arm *h* of the gate-locking device, while the spring pressed bolt 5 *i* thereof, will lie within one of the notches of said rack, and detain the gate in its closed position, as indicated by the dotted lines.

When the car is opposite any one of these gate-locks, however, the cam *a''* engages with 10 the roller *i''* upon the controlling lever *i'*, and withdraws the bolt, as shown in Fig. 2. Under these circumstances, the gate and its rack *g''* may be elevated, thus releasing the switch arm *h*, and engaging its lower contact *h'*, between the terminals *5'*, *6'*, to light the floor-signal lamp *f*. When the gate is depressed, and locked, as indicated in the lower portion of Fig. 1, however, the rack *g''* engaging 15 the extended end of switch arm *h*, presses its upper contact *h''* between the terminals *4'*, *7'*, thereby closing the circuit through the unlocking or releasing solenoid *e*, of the cable-locking mechanism.

This latter device, shown in turn in Figs. 25 3 and 4, comprises said solenoid, a plunger *e'*, the connecting link *e''* operatively associated with the gear *j*, its transversely movable rack *j'* and the gripping jaws *j''* of the cable-locking device. This entire mechanism, principally for convenience of illustration, is shown to be mounted at the top of 30 the car upon the rods *k* and between opposing springs *k'*, *k''*, so that the device is resiliently supported, in order to afford the 35 cable some freedom of movement when gripped, for a purpose which I shall now explain.

It will be noted that one of the main conductors 2 extends through the switch *l*, at 40 the top of the elevator shaft; the mechanism thereof, being best shown in Figs. 6 and 7. The switch normally stands open, as indicated in dotted lines, when the car is not in operation, for the purpose of automatically 45 preventing the continued energization of the solenoid. Said switch *l* is provided with a switch arm *l'*, adapted normally to rest in the notch of the cam *b''*, provided upon the cable sheave *b*. In this dotted line position, 50 the switch contacts are out of engagement, but a slight rotation of said cam *b''* causes the arm to ride upon its circular periphery, and engages the movable contacts *l'* with the stationary contacts *m*, for the purpose 55 of closing the circuit through the releasing solenoid *e*.

In order to accomplish this initial movement of the cable sheave, it will be observed 60 that the cable-locking mechanism is spring-mounted, so as to permit a slight movement thereof with the cable tightly gripped between the jaws *j''*, under the influence of the spring *e''*. The switch *l* automatically opens the circuit when the cable *c* is actuated 65 by the operator for bringing the car to a

standstill, and the locking mechanism at once automatically grips said cable as above explained. The switch *l*, on the other hand, invariably is closed whenever the car is in motion, through the engagement of the periphery of the circular cam *b''* with the switch lever *l'*.

The coöperation of the gate-lock switch of Fig. 2, invariably is necessary, however, in order that the car may be started from its position of rest, for the reason that the conductor 4 is opened within the gate locking appliance whenever the contact *h''* is permitted to withdraw from between the terminals *4'*, *7'*, through the opening of the associated gate.

A description of the concerted action of the several mechanisms briefly referred to above, will now be readily understood. With the car *a* standing at the second level, 85 and the gate *g*, elevated, as shown, it will be impossible for the operator, or any one on another floor to start the car, until said gate has been closed. Under these circumstances, the light *a²* in the car, is extinguished by reason of the doubly opened circuit through conductor 4, while the floor lamp *f* is lighted by the closure of the contacts *5'*, *6'*, within the gate lock switching mechanism, as shown by the full lines in 90 Fig. 2.

For convenience, the return cable *c'* runs past the different floors exteriorly of the car, so that said car may be operated from any floor, if the safety apparatus is in 100 proper co-acting relation, as will be further explained. Thus, upon closing the gate *g*, either the operator within the car, or some one upon another floor may start said car, by pulling upon the cable *c*, *c'*, sufficiently 105 to rotate the cam *b''*, for elevating the switch arm *l'*, to close the controlling circuit, inasmuch as the circuit primarily will be closed through contacts *4'*, *7'*, immediately the rack *g''* and its attached gate are 110 fully lowered, while the springs *k'*, *k''* afford sufficient play for the cable locking device, to permit of some slight independent movement of the cable against the tension, of one or the other set of said springs. 115 Lamp *a²* in the car, accordingly will be lighted, while the floor lamps will be extinguished, and said car will be caused to travel to the desired level, by any of the well known elevator motor-mechanisms, 120 which need not be shown, nor further referred to herein.

Immediately cable *c*, *c'* is brought to the position for stopping the car, however, switch *l* is automatically opened under the 125 impulse, both of the weight and spring, whereby the lever arm is caused to drop within the groove of cam *b''*. The cable gripping mechanism at once acts to engage, and hold the cable in this position, under 130

the influence of spring e^2 , since solenoid e has become deenergized. Cam a'' will be brought into engagement with the corresponding lever-arm i' , thereby actuating the bolt i to release the rack and permit the gate g to be opened. None of the other gates upon the elevator shaft in question, however may be opened, for the reason that they are mechanically locked and the car

10 cannot be moved from the opened gate, for the reason that the cable is tightly gripped and the releasing circuit is opened between contacts $4'$ and $7'$ of the gate-lock switching mechanism.

15 In Fig. 8, I have shown an extremely simple form of contact-switch containing structural features which lend themselves to the purposes of switch l above mentioned. This comprises a pivoted arm m carrying 20 the weighting rotatable roller n , adapted to travel upon the surface of cam b'' and fit within its notch when in proper position. Arm m carries the movable contact of the paired carbon contacts m' , m'' ; the latter 25 having a spring-mounting o , through which the controlling circuit may be automatically closed or may be similarly opened, upon the engagement of the roller with the notch in said cam b'' .

30 I am aware that some of the safety operating conditions just described have been separately secured by mechanism of different construction, but in none of these has there been provided the complete co-acting 35 system set forth above in some detail, and here defined as my improvement.

I accordingly assert as my invention, and desire to secure by Letters Patent, together with such modifications as may be made by 40 mere skill, the following:—

1. In apparatus of the class described, the combination with an elevator car of means for effecting the travel of the car, an electro-mechanical locking-mechanism normally acting 45 to render said means inoperative, and an automatic switch associated therewith for interrupting the movement of said means while the car is at rest, said switch being operated by the car operating means for causing it to return to its original position 50 to permit the car to be moved, substantially as set forth.

2. In apparatus of the class described, the combination with an elevator car of controlling 55 mechanism therefor, electro-mechanical means normally acting to render said mechanism inoperative, a circuit extending from any suitable source through said electro-mechanical means, and an automatic switch actuated by said controlling means to disconnect the circuit when the elevator car is stopped, substantially as set forth.

3. In apparatus of the class described, the combination with an elevator car of a plurality 60 of gates positioned along the line of

travel of said car, individual locking devices therefor, unlocking means provided upon the car, a switch, means on the gates for operating the switch, an electro-mechanical means for withholding the car from operation, a circuit extending through said electro-mechanical means, said switch in said circuit and being adapted to break the circuit upon engagement with the means on the gate, and an automatic switch in said circuit 70 adapted to coöperate with the electro-mechanical means for holding the car from operating.

4. The combination with an elevator car of an electro-magnetic appliance normally 80 operated for preventing the travel of the car, a yielding mounting therefor to permit a limited independent movement, and an automatic switch associated with the electro-magnetic appliance adapted to be closed with 85 such limited movement, substantially as set forth.

5. The combination with an elevator car of its controlling cable, an electro-magnetic cable-gripping mechanism normally oper- 90 able to prevent the actuation of the cable, a spring mounting therefor adapted to permit a limited independent movement thereof and of the cable, an automatic cut-off switch operated upon the stoppage of the car and controlled by the cable for causing said cable gripping mechanism to be operated and prevent the movement of the car, and an actuating member therefor adapted to close the switch upon the limited movement permitted 95 100 for said cable, substantially as set forth.

6. The combination with an elevator car of its controlling cable, an electro-magnetic cable-gripping mechanism normally operable to prevent the actuation of the cable, a 105 spring mounting therefor, adapted to permit a limited independent movement thereof and of the cable, a gate lock disabling switch associated with the gate lock, an automatic cut-off switch operated upon the stoppage of 110 the car and controlled by the cable for causing said cable gripping mechanism to be operated and prevent the movement of the car, and an actuating member therefor, adapted to close the switch upon the limited 115 movement permitted for said cable, substantially as set forth.

7. The combination with the controlling means for an elevator car, of an electrically actuated safety apparatus for said car, a 120 switch for governing the action of said safety apparatus, a cam associated with said controlling means adapted to have engagement with the switch for maintaining it in position whereby the car may be operated, said cam being provided with means for causing the switch to become disengaged whereby the safety apparatus will be operated to prevent the movement of the car.

8. The combination with car controlling 130

means of the cable type and cable gripping members therefor, of a spring under tension to force said members into their gripping position, electro-magnetic means for normally opposing said spring, an automatic switch associated with said magnetic means, an electric circuit extending to said magnetic means and switch, and means operable by said controlling means for causing the automatic switch to be moved for opening and closing the circuit, to cause the gripping members to engage or disengage the car controlling means.

9. In apparatus of the class described, the combination with two toothed gripping

members of a rack operatively engaging said toothed members, means for actuating the rack, including a spring tensioned means to force the gripping members into gripping position, and a solenoid normally energized to overcome the spring tension, and for maintaining the gripping members inert, substantially as set forth. 20

In testimony whereof I do now affix my signature in the presence of two witnesses. 25

JOHN MUTTON. [L. S.]
